[57] **CLAIM**

The ornamental design for a resilient grip sleeve for an air tool, as shown and described.

DESCRIPTION

FIG. 1 is a front right top perspective view of a resilient grip

1 Claim, 4 Drawing Sheets

sleeve for an air tool showing a first preferred embodiment of our new design;

FIG. 2 is a front bottom perspective view thereof;

FIG. 3 is a front left top perspective view thereof;

FIG. 4 is a rear bottom perspective view thereof;

FIG. 5 is a right side elevational view at a reduced scale. The broken line showing of an air tool in FIG. 5 is for illustrative purposes only and forms no part of the claimed design;

FIG. 6 is a front right top perspective view of a resilient grip sleeve for an air tool showing a second preferred embodiment of our new design;

FIG. 7 is a front bottom perspective view thereof;

FIG. 8 is a front left top perspective view thereof;

FIG. 9 is a rear bottom perspective view thereof; and,

FIG. 10 is a right side elevational view at a reduced scale. The broken line showing of an air tool in FIG. 10 is for illustrative purposes only and forms no part of the claimed design;

FIG. 11 is a front right top perspective view of a resilient grip sleeve for an air tool showing a third preferred embodiment of our new design;

FIG. 12 is a front bottom perspective view thereof;

FIG. 13 is a front left top perspective view thereof;

FIG. 14 is a rear bottom perspective view thereof;

FIG. 15 is a right side elevational view at a reduced scale. The broken line showing of an air tool in FIG. 15 is for illustrative purposes only and forms no part of the claimed design;

FIG. 16 is a front right top perspective view of a resilient grip sleeve for an air tool showing a fourth preferred embodiment of our new design;

FIG. 17 is a front bottom perspective view thereof;

FIG. 18 is a front left top perspective view thereof;

FIG. 19 is a rear bottom perspective view thereof; and,

FIG. 20 is a right side elevational view at a reduced scale. The broken line showing of an air tool in FIG. 10 is for illustrative purposes only and forms no part of the claimed design.
